United States Patent Office

Des. 175,316
Patented Aug. 9, 1955

175,316

LEASH HANDLE

Ralph Roccia, Camden, N. J.

Application May 11, 1954, Serial No. 30,415

Term of patent 7 years

(Cl. D38—1)

Fig. 1 is a face view of a leash handle, showing my new design, and

Fig. 2 is a side view of the leash handle.

I claim:

The ornamental design for a leash handle, substantially as shown.
